Smith & Lammons.

UNITED STATES PATENT OFFICE.

PALMER ABERDEEN, OF TORONTO, ONTARIO, CANADA.

ATTACHMENT FOR MAINTAINING KEYS IN KEYHOLES.

Application filed December 13, 1924. Serial No. 755,795.

To all whom it may concern:

Be it known that I, PALMER ABERDEEN, of the city of Toronto, Province of Ontario, Dominion of Canada, attorney, subject of the 5 King of Great Britain, having invented certain new and useful Improvements in Attachments for Maintaining Keys in Keyholes, do hereby declare that the following is a full, clear, and exact description of the 10 same.

My invention relates to a device adapted to insert into a key hole in combination with the key, to maintain and prevent it from being forced out, or turned, by instruments in- 15 serted through the key hole from the opposite side of the lock from that in which the key has been turned to lock the door.

The device is constructed that it may be readily inserted into any size or shape of 20 key hole, with and while the key is in the lock.

A flange is formed around the shank adjacent with that portion adapted to engage in the key hole, for the purpose of effectively closing the key hole from observation 25 from the opposite side of the door, and to prevent inserting the device too far into the key hole.

The shank of the device is constructed 30 whereby it may be lengthened out to adapt it to be used with extra long keys, and keys of various lengths.

The device is adapted to be used with any 35 of the standard length and shape of keys, as the claw member for engaging with the key is held in adjustable relation on the shank, by a tension spring, and may be adjusted and maintained in adjusted position by the spring.

40 The claw member is held by the spring, and may be instantly disengaged from the key for the purpose of unlocking the door, either in the ordinary way, or for hasty exit.

The claw member which engages the head 45 of the key, is manipulated simply by the thumb and finger.

When the device is disengaged from the key hole and out of use, the claw member 50 may be folded down in compact relation, so that the device may be conveniently carried in the pocket, or hung on a key ring by a loop formed on the end of the shank for that purpose.

The object of the device is to provide means by which a key may be safely held in locked 55 relation in a door lock, and protected from being unlocked, or turned or removed, by the insertion of instruments through the key hole from the opposite side of the lock than that in which the key is inserted. 60

In the drawings:—

Figure 1 is a perspective view of a portion of a door and lock showing the device in position and in engagement with a key;

Figure 2 is a top plan view of the device; 65

Figure 3 is a side elevational view of the device;

Figure 4 is a side elevational view of the device showing the claw adjusted out, and

Figure 5 is a top plan view showing the 70 stem extended outwardly.

Like letters of reference refer to like parts throughout the drawings.

The letter *a* designates a shank, consisting of an externally screw threaded stem *b* and 75 an internally screw threaded sleeve *c*, adapted to be longitudinally adjusted by screwing the stem in or out of the sleeve.

d designates a locking ring screw adjustable on the stem *b*. The ring is adapted to 80 be screwed up against the end of the sleeve *c*, after the stem has been screwed in or out, to maintain the adjusted positions.

The periphery of the ring is milled to provide a finger grip to facilitate in manipulating it. 85

Formed on the outer end of the stem *b* is a curved tongue *e* adapted to be inserted into the key hole, by which the device is supported in lateral relation therefrom. 90

f represents a flange formed with the tongue *e*, and at the junction of the tongue and the stem *b*.

The flange *f* is adapted to engage over the lower part of the keyhole when the tongue 95 is inserted into the key hole, to prevent the insertion of any kind of an instrument through the key hole, to turn or force out the key.

When attaching the device to the lock, the 100 shank is held in a position that the tongue will enter into the key hole at an angle. It is then forced inwardly until checked by the engagement of the flange *f*, when it is then straightened out, which brings the curved 105 centre portion and the end of the tongue

into engagement in binding relation against the side walls of the key hole, by which it firmly holds, and closes off the passage through the key hole.

5 *g* designates an adjustable claw member adapted to engage and attach over the end of the key and firmly hold it in the lock, so that it cannot be turned or forced out of the lock, by manipulation through the key hole, 10 from the opposite side of the door from that in which the key is inserted.

The claw member *g* is held in pivotal and 15 slideable relation with the sleeve *c* by pintles *h* formed therewith and projecting inwardly therefrom.

The pintles engage in slots *i* formed in longitudinal relation in the sleeve *c*, which allows the claw member to be adjusted from a folded position against the sleeve, to a vertical or right angle position therewith, and also to adjust along the sleeve to adapt it to engage with keys of various lengths.

The head portion of the claw member is bifurcated so as to engage around the stem of 25 the key, and formed in the bifurcated portions are notches *k*, which engage over the head of the key to prevent it from being turned, and further secure it from being manipulated from the opposite side of the 30 lock.

m is a coiled tension spring which encircles the shank *a*, in between the locking ring *d* and the claw member *g*.

The spring *m* is for maintaining an adjustable tension against the claw member, to allow for adjusting to engage over the head of the key. The spring *m* also holds the claw member firmly against a flange *n* formed on the end of the shank, when the 40 claw member is folded down into compact relation against the sleeve.

Formed on the outer end of the shank is

an eye *o* by which the device may be attached to a key ring or watch chain when out of use.

Slight modifications may be made in the shape and arrangement of the different parts without deviating from the nature of my invention.

What I claim as new and desire to secure 50 by Letters Patent is:—

1. A device of the class described, a shank adapted to be longitudinally adjusted, said shank comprising a screw threaded spindle and an internally screw threaded sleeve, a 55 curved tongue formed on the outer end of said spindle, a claw member slidably and pivotally arranged on the said sleeve, a tension spring for maintaining the said claw member in adjusted positions on the said shank, substantially as and for the purpose specified. 60

2. A device of the class described, a shank adapted to longitudinal adjustment, said shank comprising a screw threaded spindle 65 and an internally screw threaded sleeve, a locking ring set on the said spindle, a curved tongue formed on the outer end of the said spindle, a radially extending flange formed with the said tongue, slots formed in longitudinal relation in the said sleeve, a bifurcated claw member adjustably arranged on said sleeve, pintles formed with the said claw member, said pintles engaging in the 70 said slots, said claw member adapted to 75 slideable and pivotal adjustment, a tension spring encircling the said sleeve, said spring adapted to maintain said claw member in adjusted positions on the said sleeve, substantially as and for the purpose specified. 80

In testimony whereof, I have affixed my signature to this specification.

Toronto, December 6th, 1924.

PALMER ABERDEEN.
